Primary Examiner — Jennifer L Watkins*Assistant Examiner* — Samantha Lynne Brodowski(74) Attorney, Agent, or Firm — Dunlap Bennett & Ludwig, PLLC(57) CLAIM

The ornamental design for a message panel for a bag, as shown and described.

DESCRIPTION

FIG. 1 is a top front perspective view of a message panel for a bag, showing my new design;

FIG. 2 is a front elevation view thereof;

FIG. 3 is a top plan view thereof;

FIG. 4 is a bottom plan view thereof; and,

FIG. 5 is a right-side elevation view thereof, the left-side elevation being a mirror image thereof.

The evenly spaced broken lines showing a bag depict environmental subject matter and form no part of the claimed design.

1 Claim, 3 Drawing Sheets(56)
